FOLDING DRAINBOARD

Henry W. Altorfer, Peoria, Ill.

Application December 30, 1938, Serial No. 248,377

3 Claims. (Cl. 68—264)

This invention relates to an improved drainboard structure for domestic washing machine wringers.

5 Wringers are notorious dust catchers, and one of the first chores for the careful laundress is to carefully clean the wringers and rolls.

The growing practice of decorating and furnishing basements for recreation rooms has led to more attention to the general appearance of 10 the laundry room and the laundry equipment. This has been reflected by a desire to improve the general appearance and utility of washing machines.

Also there has been a growing tendency to 15 place the laundry equipment upstairs, as in kitchens, and this has created a demand for better or more appropriate appearance as grouped with other kitchen equipment, such as cabinets, refrigerators, sinks, etc.

20 It will be obvious that the wringer, projecting as it does above the top of the machine, should be removed.

The particular object of the invention is to 25 provide an improved drainboard which will fold upward to enclose the rolls within the frame of the wringer and thus prevent the roll from becoming soiled from dust and the like.

Another object is to provide a folding drainboard structure that will greatly decrease the 30 bulk of the wringer so that it will clear the top of the washer to enable it to be used as a table top and generally to enhance the appearance of the machine when not in use.

And a still further object is to reduce the bulk 35 of the wringer to a comparatively narrow, flat shape so as to facilitate its removal from the machine and its storage in limited space and thus leave the washer free of any wringer obstruction.

40 Other objects and benefits will be disclosed in the accompanying descriptions and drawings in which:

Fig. 1 is a side elevation view of the wringer with the drainboards in closed or folded position;

45 Fig. 2 is an enlarged sectional elevation view of the wringer as it would appear on the section lines 2—2 of Fig. 1 with one drainboard closed or folded and the other drainboard open or extended;

50 Fig. 3 is an enlarged broken sectional plan view of the wringer as shown in Fig. 2, as it would appear on the section lines 3—3 of Fig. 2; and

Fig. 4 is an enlarged isometric view of one of the drainboards to better show its structure.

55 Now referring to Fig. 1, I show a modernized

wringer structure wherein the numeral 10 designates the lower frame which extends and completely encloses the wringer head. The upper frame 11 extends over and for the full length of the lower frame. On the upper frame 11 is 5 mounted a safety release lever 12, and on the right hand end of the lower frame is a wringer head control handle 13. A pressure reset handle 14 is mounted on the opposite end of the lower frame. Directly under the wringer head is a 10 pivot post 15 adapted to be inserted in a wringer support tube mounted in the frame of the washer. Extending from the pivot post 15 is a drive shaft 16 in which is inserted a drive pin 17 adapted to be engaged by a drive coupling in the wringer 15 tube.

Now referring to Fig. 2, the drainboard 21 is pivotally mounted on a pin 22 in the lower frame and a clothes shield 23 is pivotally mounted on the drainboard 21 by a pin 24. This shield 23 is 20 urged to counter-clockwise rotation by a torsion spring 25, as shown. The clothes shield 23 thus urged by the spring 25 bears against the end shields 20 at the notch 23', as best shown in Fig. 3. It will be obvious that as the drainboard 21 25 is moved upward to enclose the rolls 18 and 19, the clothes shield 23 will slide upward against the end shield 20, assuming the position as shown on the left hand side of Fig. 2. It will be obvious that by this structure water drained from the 30 rolls 18 and 19 will be deflected by the flipper board 26 onto the drainboard 21.

Now referring to Fig. 3, a sliding bar latch 28 is mounted in the lower frame and urged outward by a compression spring 30. This latch is 35 controlled by a finger button 29 in order that it may be retracted from the notch 28' of the drainboard 21, in order to permit the drainboard 21 to be folded upward into closed position as shown in the left hand side of Fig. 2. A detent embossment 31 is put in the sides of the drainboard 21 40 in order to hold the drainboard firmly in closed position.

It will be noted that in Fig. 4, wherein the drainboard 21 is shown in an enlarged isometric view, that certain of the elements in the structure are not needed, for instance one of the notches 28'. In explanation of this it will be stated that this is done to avoid multiplicity of parts and in order to make the drainboard 21 45 suitable for mounting on both sides of the wringer. Otherwise the holes 22' and 24' are used for mounting the pins 22 and 24, respectively. The embossed detents 31 are on both ends of the drainboard.

From the foregoing description it will be apparent that the drainboards can be lowered to open position as shown on the right hand side of Fig. 2 where they are held firmly in position by the latch 28. In this position the water from the rolls 18 and 19 is deflected by the flipper board 26 onto the drainboard 21, the transfer being positively made by the cooperating lips 21' and 26'. Further, the drainboard can be raised to closed position, as shown in the left hand side of Fig. 2, by releasing the latch 28 by means of the button 29 where they are firmly held in closed position by the detents 31. In this closed position it will be obvious that the rolls and drainboards are completely protected against dust and the wringer has been folded into a compact, flat shape whereby it can be easily handled and stored.

Having thus described my invention, I claim:

1. In a wringer for a domestic clothes washer, lower and upper frames, a pair of cooperative pressure rolls, a pair of roll end shields, drainboards pivotally mounted in side openings of the lower frame, inwardly inclined clothes shields pivotally mounted longitudinally on the drainboards adjacent the lower roll, said clothes

shields being spring urged into contact with the roll end shields, detents on the drainboards to hold same firmly in closed position in the drain openings and releasable spring latches to hold the drainboards in lowered or open position.

5

2. In a wringer for a domestic clothes washer, lower and upper frames, a pair of cooperative pressure rolls, side openings in said frames exposing the rolls, drainboards pivotally mounted in said openings, inwardly inclined longitudinal clothes shields pivotally mounted and spring-torsioned inward on said boards, and detent means to lock the drainboards in lowered, open position and lock means to retain them in closed, folded position.

10

3. In a wringer for a domestic clothes washer, lower and upper frames, a pair of cooperative pressure rolls, side openings in said frames exposing the rolls, drainboards pivotally mounted in said openings, inclined clothes shields on said boards pivotally mounted and spring-torsioned inward adjacent the lower roll, and means to lock the drainboards in lowered, open position and means to retain them in closed, folded position.

20

HENRY W. ALTORFER.
